ABSTRACT

This disclosure relates to a driving circuit for driving a coil of an electromagnet for the actuation of a hammer in a high speed impact printer of data handling systems, which driving circuit includes first switching means upstream of the coil, second switching means downstream of the coil, current sensing means for sensing current in the coil, a closed unidirectional current path including the second switching means, the coil in a diode, first control circuit means for actuating the first switching means in response to an input control signal, second control circuit means for switching on the second switching means in response to the first input control signal and for the entire duration of the input control signal, and a bistable device triggered by the current sensing means to assume one of two electrical states when the sensed current reaches a predetermined value and to provide an output signal corresponding to that one state, the output signal being effective to switch off the first switching means even in the presence of the input control signal.

6 Claims, 3 Drawing Figures

FIG. 3

DRIVING CIRCUIT FOR PRINTING ELECTROMAGNET

The present invention deals with driving circuits for high speed electromagnets, such as those used for hammer actuation in high speed impact printers for data handling systems.

Such driving circuits must fulfill particular requirements. Thus, they must provide fast magnetization of the electromagnet, they must have repeatability with a limited spread of the kinetic energy imparted to the printing hammer in the various and subsequent energizations, as well as during the entire actuation time of the latter.

Among the various solutions used to achieve such results, there are voltage controlled energization systems which use a first higher voltage for energization and a second lower maintenance voltage applied during suitable and subsequent time intervals. This requires the use of a power supply having very accurate voltage control. Further, in order to assure the complete magnetization of the circuits in each instance, prior art devices are known to have marked a waste of energy, and to use an oversized power supply thus raising the cost of the equipment.

The present invention has for its object a driving circuit which satisfies the above requirements and avoids the above inconveniences, providing in addition further advantages. In particular, the circuit according to the invention:

- a. provides magnetomotive force sufficient for magnetic core saturation and which assures the appropriate attracting force;
- b. reduces to a minimum extent the power drained from the power supply and uses to a maximum extent the energy stored in the electromagnet inductance;
- c. enables the electromagnet to be driven by an unstabilized voltage supply;
- d. reduces the risk of catastrophic damage and may be kept under voltage supply even in case of failure and has self diagnostic capability.

The driving circuit according to the invention includes in series connection a first and a second current switch respectively upstream and downstream of the electromagnet winding or coil and a unidirectional short circuit path for the coil, in which path the second switch is included. The invention further includes a current detector, a bistable circuit and a control circuit which opens the first switch when the current flowing in the coil reaches a preestablished value.

According to another aspect of the invention the circuit additionally includes a second current detector associated with the bistable circuit to detect current flowing through the first switch and to open it when such current exceeds a safety limit.

According to still another aspect of the invention, the circuit additionally includes a voltage detector to provide an indication of the voltage existing at a coil terminal, the voltage detector and the bistable circuit providing logical information which allows one to check the correct circuit operation and, in case of failure, to identify faults in the circuit components.

These and other features of the invention will appear more clearly from the following description of a preferred embodiment and from the attached drawings wherein:

FIG. 1 is a block diagram of a driving circuit according to the invention.

FIG. 2 shows a wiring schematic of a preferred embodiment of the driving circuit according to the invention.

FIG. 3 is a timing diagram of the operation of the circuit according to the invention.

Referring now to FIG. 1, the circuit according to the invention is shown in block diagram form.

The coil 1 of a printing electromagnet is connected between a voltage source + V and a reference point or ground, through two switches 2 and 3, preferably of the electronic type respectively placed upstream and downstream of the coil, and connected respectively to the winding terminals 4 and 5.

A diode 6 is connected between ground and terminal 4 and is conducting, in relation to the voltage supply, which by example has been chosen positive, from ground towards terminal 4.

A current detector 7 is interposed between switch 3 and ground and has an output 70 which controls a bistable device 8. The bistable device 8 has a second control input in the form of an output 10 of a voltage detecting circuit 9, which provides a signal indicative of the voltage existing at terminal 5.

The bistable device 8 is set to a first electrical state, designated "set" when the current detected by detector 7 reaches a preestablished value, and is reset to a second electrical state when the voltage at terminal 5 reaches or exceeds a preestablished value detected by circuit 9. The two switches 2 and 3 are controlled by control circuits 11 and 12, respectively.

When a suitable electrical signal is applied to an input terminal 15 of the driving circuit, wires 13 and 16 transfer such signal to the inputs of the control circuits 11,12 which operate to close the switches 2 and 3. Switch 3 remains closed for the whole time during which the electrical control signal is present at input 15. However, switch 2 remains closed for a shorter time. This is due to the fact that output 14 of the bistable device 8 is connected to a second input of the control circuit 11.

As soon as the current flowing in coil 1 reaches a preestablished value, which is chosen as being adequate to saturate the magnetic core of the coil 1, the bistable device 8 issues a signal which is applied to control circuit 11 and commands the opening of switch 2. At this point the current flowing in the coil 1 continues to flow in the closed path formed by diode 6 and switch 3 and decreases at an exponential rate which depends on the time constant of the circuit. When the control signal applied to input 15 is removed and switch 3 is opened, the overvoltage due to the opening is detected at terminal 5 by circuit 9 and bistable device 8 is reset. Thereafter, a new operating cycle of the electromagnet may start.

It is clear from the foregoing that the electromagnet is energized by an initial voltage which may be chosen so high as to magnetize and saturate the circuit in a very short time.

As soon as magnetization is achieved, no more energy is supplied to the circuit.

If a suitably high voltage supply is used, saturation of the magnetic circuit is achieved before the customary electromagnet keeper accomplishes a substantial displacement from its rest position, so that the energy stored in the air gap may be converted nearly in its en-

tirety into kinetic energy of the keeper. On the other hand, it is known that in a magnetic circuit provided with air gap, the energy stored in the gap is the most relevant fraction of the magnetization energy supplied to the whole circuit. Therefore, the driving circuit according to the invention provides a rational utilization of the energy supplied to the electromagnet. In addition, since the driving circuit is controlled by a quantity (current) related to the magnetization status of the coil, it is largely insensitive to changes in the voltage supply.

In FIG. 2 there is illustrated in detail a preferred embodiment of the driving circuit according to the invention. The functional blocks discussed relative to FIG. 1 are set off in FIG. 2 by means of dotted lines and are identified by the same reference numerals.

Switch 2 is now specifically disclosed as a transistor having an emitter connected to terminal 4 of coil 1. A collector of the transistor switch 2 is connected to a voltage source $+V_1$, having a rather high value (for instance 45 V), through a resistor 116 which has a very low value (for instance 0.1 Ω).

Switch 3 is now specifically disclosed as a transistor having its collector connected to terminal 5 of coil 1 and its emitter connected to ground through a resistor 17 which has a very low value (for instance 0.2 Ω).

Control circuit 11, which controls transistor switch 2, comprises transistors 23, 24, pulse transformer 25 and certain resistors and diodes to be described hereinafter. Transistor 24 has an emitter connected to ground, while its base is connected to the input terminal 15 through a diode 28, whose conducting direction is from the input to the base. In addition, the base of transistor 24 is connected to a second control terminal 31 through a resistor 30.

When, at least one of the control terminals 15 and 31 is at a positive voltage, transistor 24 is conducting and its collector is at voltage a very close to ground. Thus, transistor 23, the base of which is connected to the collector of transistor 24, is off and no current flows in the primary winding of pulse transformer 25.

When both the terminals 15 and 31 are at a voltage close to ground (or negative) transistor 24 is off and transistor 23 is conducting. Therefore, transformer 25 is fed by a voltage pulse, which is transferred to the secondary winding and commands the switching on of transistor switch 2. The size of transformer 25 is chosen so as to avoid saturation for the maximum foreseeable duration of the control pulses.

The collector current flowing through resistor 21 causes a voltage drop across the resistor, so that the collector voltage rises. Thus, the base-emitter junction of transistor switch 3, is forward biased to render the switch conductive. Transistor switch 3 remains conductive for the entire duration of the control pulse.

Transistor 23 has its collector connected to a suitable voltage source $+V_2$, through the primary winding of the transformer 25 and a current limiting resistor 26. The emitter of transistor 23 is connected to ground. The terminals of the secondary winding of the transformer 25 are connected respectively to the base and to the emitter of switching transistor 2. The base of transistor 23 is also connected to a voltage source $+V_3$, through resistor 27.

Resistor 17 constitutes a current detecting device. The voltage drop produced by the current across the resistor 17 (which current, by neglecting the negligible

base current of transistor switch 3, is also the current flowing in the coil) provides a voltage indication proportional to such current.

In order to assure the demagnetization of the transformer 25, a Zener diode 32, connected in opposition to a diode 33, provides a unidirectional short circuit path.

A control circuit 12, which controls transistor switch 3, includes a transistor 18, for instance of PNP type, and resistors 19, 20, 21, 22. A control terminal 15 is connected to the base of transistor 18 through resistor 22. The emitter of transistor 18 is connected to a voltage source $+V_3$ and the collector thereof is connected both to the base of transistor 103, through resistor 20 and to ground, through resistor 21.

Normally the input control terminal 15 is kept at a positive voltage so that transistor 18 is non-conductive and the collector of transistor 18 is at ground potential. Therefore, transistor switch 3 too is non-conductive. Upon the application of a control pulse to the input terminal 15, the potential of the latter approaches ground potential, so that the base-emitter junction of transistor 18 becomes forward biased and transistor 18 becomes conductive.

The use of a pair of switches, enables one to provide the driving circuit with diagnostic circuit devices in order to detect and to identify the faults of the same. Further, the probability of catastrophic failure is reduced due to the fact that the probability of a multiple failure of both switches is lower than the probability of a simple failure of a switch.

Control terminal 31 is driven by the bistable circuit 8. In a preferred embodiment the bistable circuit 8 includes an amplifier 34, a transistor 35 and certain diodes and resistors. The inverting input of the amplifier 34 is connected to the emitter of transistor switch 3 through resistor 36 and receives a voltage signal proportional to the current flowing in coil 1. The non-inverting input of the amplifier 34 is connected on one side to a voltage source $+V$ through resistor 37 and on the other side to ground, through resistor 38. In addition the non-inverting input of amplifier 34 is connected to the output of the amplifier through resistor 39 and diode 40. Diode 40 has a conductive direction from the input to the output of the amplifier.

When transistor switch 3 is open, the inverting input of amplifier 34 is at ground potential. Resistors 37 and 38 are chosen of a value so as to apply to the non-inverting input a voltage that is slightly positive. The output of the amplifier 34 is therefore at a positive level and diode 40 is reverse biased.

When transistor switch 3 is closed and current flows in the coil 1 and in resistor 17, the voltage drop across resistor 17 tends to raise the voltage applied to the inverting input of the amplifier 34. For a suitable value of the current flowing in the coil 1 and corresponding to the saturation current for the coil, the voltage applied to the inverting input exceeds the voltage applied to the non-inverting input and the output voltage becomes negative. Diode 40 becomes conductive and lowers the voltage applied to the non-inverting input, causing a positive feed-back which saturates the amplifier 34 and maintains it in that state even when the current in resistor 17 goes to zero and the voltage applied to the inverting input goes to ground.

The output of amplifier 34 is connected through resistor 41 to the base of transistor 35, whose collector

is connected to the voltage source $+V_3$ through resistor 43 and whose emitter is connected to ground. A diode 44 between the base of transistor 35 and ground, the direction of conduction of which from ground to base, prevents the application of too high a reverse bias to the base of transistor 35. The collector of transistor 35 is further connected to the input terminal 31. When the voltage at the output of amplifier 34 is positive, transistor 35 is conductive and its collector is substantially at zero voltage, as is the input terminal 31. Therefore, the state of transistor 24 in the control circuit 11 depends on the voltage applied to terminal 15.

When the voltage at the output of amplifier 34 is negative, transistor 35 is switched off. Its collector, as well as input terminal 31, are then at a positive potential. Irrespective of the voltage applied to terminal 15, transistor 24 is kept in its conductive state and transistor 23 and transistor switch 2 are switched off. Therefore, as soon as the current flowing in the electromagnet, of which coil 1 is a part, reaches a predetermined value suitable to saturate the magnetic core, the above-described circuits intervene to cause the switching off of transistor switch 2 to be switched off and to remain non-conductive in its stable condition.

However, the current flowing in coil 1 is not switched off and the self-induced electromotive force in the circuit sustains the current which may flow through diode 6. Only at the termination of the control pulse applied to terminal 15, when transistor switch 3 is opened, is the residual current flowing in the coil 1 switched off. The self-induced voltage caused by this switching action is used to reset the bistable circuit 8. To this purpose, such voltage is applied through a voltage divider formed by series, connected resistors 46,47 (which are connected on one side of terminal 5 and on the other side to ground) and through diode 45 to the non-inverting input of amplifier 34. Such voltage is sufficiently high to bring the potential of the non-inverting input to a potential higher than the one applied to the inverting input so that the output of the amplifier 34 becomes positive. In order to limit the self-induced voltage which is generated by transistor switch 3 switching off, terminal 5 is connected to the voltage source V_1 through diode 42 so that the self-induced voltage cannot exceed the value of voltage source V_1 .

The remainder of the driving circuit consists of protective devices. Maximum current protection is achieved by means of resistor 116, transistor 48 and resistor 49. Transistor 48 (of PNP type) has its emitter connected to the voltage source V_1 and its collector connected to the inverting input of amplifier 34, through resistor 49. Its base is connected to the collector of transistor switch 2.

If, for some reason the current flowing in resistor 116 exceeds a predetermined value, transistor 48, normally open, starts conducting and applies to the inverting input of the amplifier 34 a positive voltage which causes the intervention of bistable circuit 8 and the switching off of transistor switch 2.

Some examples of causes of failure to bring about the foregoing action are as follows:

- a. short circuit of diode 6.
- b. short circuit of coil 1.
- c. transistor switch 2 emitter grounded.

A further device which provides indirect protection consists of a voltage detector connected to terminal 4 of the coil 1. Such a circuit may consist of a voltage di-

vider, including resistors 50, 51 and a threshold circuit 52 having an input connected to such voltage divider so as to provide an output signal of a first level when the input voltage is lower than a threshold voltage, and an output signal of a second level when the input voltage is higher than the threshold voltage. The threshold circuit 52, as well as amplifier 34 are conventional circuits which are commercially available as integrated devices and therefore they need not be described in detail.

An output terminal E of the threshold device 52 provides a signal which, jointly with the signal present at the collector of transistor 35 (terminal D), provides a heretofore unavailable degree of diagnostic power for detecting failures and for fast activation of the protection circuit.

FIG. 3 is a timing diagram showing the operation of the driving circuits and enables one to evidence the utility of signals present at terminals D, E. In the diagram, the waveform designated by the reference numeral 15) represents the control voltage applied to input terminal 15. The waveforms designated D) and E) represent the signals at terminals D and E respectively, while I) represents the current flowing in coil 1.

At the beginning, the input control signal is at a positive value, no current is flowing in the coil 1 and terminals E and D are at zero voltage. At instant t_0 the input control signal is lowered to zero level. At instant t_1 , with a delay which depends on the intervention time of the control circuits, transistor switches 2 and 3 start conducting and current starts flowing in coil 1. Therefore, at instant t_1 , the signal at terminal E rises to a positive level. When the current I) reaches a predetermined value (instant t_2), the bistable circuit 8 is set and the signal at terminal D rises to a positive level. Therefore, transistor switch 2 is controlled to switch off, such action occurring with some delay at instant t_3 . At instant t_3 the voltage at terminal 4 decreases and the signal at terminal E goes to zero level.

With a predetermined delay from T_0 , at t_4 , the input control signal is raised again to a positive level so as to command the opening of transistor switch 3. This occurs with some delay starting from instant t_5 , in which the self-induced voltage caused by the circuit opening resets the bistable circuit 8, lowering to zero level the signal at terminal D.

In normal operation, at instant t_0 the voltage at terminals E,D is zero, while at instant t_4 the voltage at D is positive and the voltage at E is zero. Voltage levels different from the ones indicated above and detected at instants t_0, t_4 are indicative of failures.

Among the serious failures which may occur are the following:

- a. Short circuit of transistor switch 2. It causes the terminal 4 to remain in tension, so that at instant t_4 signal E remains at positive level.
- b. Open steady state of transistor switch 2. It prevents the energization of the coil 1, so that the bistable circuit 8 is not triggered at instant t_3 . At instant t_4 signal D is still at zero level.
- c. Short circuit of diode 6, or transistor switch 2 emitter grounded. It causes, as already seen, the intervention of the protection circuit and the set of bistable circuit 8. On the other hand there is no current flowing in the coil 1 so that bistable circuit 8 is not reset. Therefore at instant t_0 of a subsequent

- input control pulse the voltage level at terminal D will be positive instead of zero.
- d. Transistor switch 3 steadily in off state. No current can flow in the coil 1: the bistable circuit 8 is not set and at instant t_4 terminal D is still at electrical level zero.

From the foregoing description, it will be clear that the circuit described, which forms the subject matter of applicants' invention, provides a number of advantages, as discussed above. Specifically, the invention provides greater efficiency, reliability and safety than heretofore available in comparable circuits, as well as in improved ability to diagnose failures.

The driving circuit described constitutes a preferred form of embodiment of the invention. Numerous changes, modifications and substitutions will now occur to those skilled in the art, all of which fall within the spirit and scope of the invention, as defined by the appended claims.

We claim:

1. Driving circuit for driving an electromagnet coil with a controlled current comprising: first switching means upstream of said coil and connected thereto; second switching means downstream of said coil and connected thereto, current sensing means connected to said coil for sensing the current in said coil; a closed unidirectional current path including said second switching means, said coil and a diode; first control circuit means connected to said first switching means for actuating said first switching means in response to an input control signal; second control circuit means connected to said second switching means for switching on said second switching means in response to said input control signal and for the entire duration of said input con-

trol signal; a bistable device connected to and triggered by said current sensing means to assume one of two electrical states when the sensed current reaches a pre-established value and to provide an output signal corresponding to said one state, said output signal being connected to said first control circuit means and effective to switch off said first switching means even in the presence of said input control signal.

2. Driving circuit as claimed in claim 1 further comprising overvoltage detecting means to detect an overvoltage due to the switching off of said unidirectional current path and to provide an overvoltage signal, said overvoltage signal being applied to said bistable device, said bistable device being reset in that one of the electrical states other than said one by said overvoltage signal.

3. Driving circuit as claimed in claim 1 wherein there is a voltage detector connected to said coil between said coil and said first switching means.

4. Driving circuit as claimed in claim 3 wherein there is voltage signal means connected to and operated in response to the condition of said bistable device for diagnosing element failure.

5. Driving circuit as claimed in claim 1 wherein there is voltage signal means connected to and operated in response to the condition of said bistable device for diagnosing element failure.

6. Driving circuit as claimed in claim 1 wherein said first control circuit means includes a transformer having a primary winding, and demagnetization means for said primary winding including means defining an unidirectional short circuit path.
